FERROMAGNETIC "N" COUNTER

John M. Motil, Ottawa, Ontario, Canada, assignor to
Northern Electric Company Limited, Montreal, Quebec, Canada

Filed Sept. 24, 1962, Ser. No. 225,522

5 Claims. (Cl. 235—92)

This invention relates to a counting device utilizing a ferromagnetic counting unit.

Many devices and circuit arrangements have in the past been developed for counting discrete events which are capable of being translated into electric signals or pulses. Many such arrangements comprise so-called flip flop or bistable circuits having only two stable conditions with the result that a high capacity counting arrangement involves many components and relatively high cost. This is so because, with a binary system of this type it is necessary, in order to be able to accommodate the counting of a large number of events, to have a correspondingly large number of flip-flop circuits connected, one after the other so as to provide the required counting capacity. Moreover, the data yielded by a counter of this type is necessarily in binary form and, if a decimal read-out is to be obtained, relatively complicated translation circuits are required. In some other, prior counter proposals various assumptions are made concerning the timing or duration of events to be counted and, while these are satisfactory in cases where the assumptions are satisfied under operating conditions, the arrangements in question are not satisfactory where the events to be counted are of extremely variable duration or are of random occurrence. In still other prior counter arrangements multi-winding relays are used, thus complicating the circuit and rendering the design relatively more expensive. Finally, so far as I am aware, most prior counter circuit arrangements must be designed for a fixed base n (such as multi-vibrators in which n can be 2 only), thus limiting their usefulness and flexibility.

It is accordingly an object of my invention to provide, within the limitations imposed by the speed of operation of relays, a counting device which, with a minimum of components including a relay having but one winding, is capable of counting a plurality of events n , and in particular the useful facility $n=10$ so as to give decimal data, and at the same time providing a counter arrangement in which " n " can be simply varied and which is capable of recording events of random duration and frequency.

I have found that an extremely useful counting device can be obtained, capable of counting a plurality of events $n=1$ to $n=n$, by a circuit arrangement which includes a relay requiring but a single winding and at least one transfer contact, a resistor, a resistor-condenser series combination, a source of D.C. potential, and a trigger adapted to be actuated upon the occurrence of each of the events. In accordance with my invention I arrange the winding of the relay to be connected through the resistor across the terminals of the source of potential so as to set up a "holding" current in the winding. I further provide circuit connections, which include the trigger and the relay contacts, whereby, prior to the occurrence of the first event $n=1$, the series combination is connected across the source so that the condenser becomes charged. Upon occurrence of the said first event $n=1$, the trigger is caused to move from its normal position so as to connect the series combination across the terminals of the winding, thus causing the relay to close as a result of the condenser discharging into the winding. At some time during or after the occurrence of the event $n=1$, and prior to the occurrence of the event $n=2$, the trigger

2

returns to its normal condition whereby (due to the change in condition of the relay) the series combination is shorted so as to discharge the condenser, the series combination is shorted so as to discharge the condenser, the relay in the meantime remaining in closed position due to the holding current. Thereafter, upon the occurrence of each of the events $n=2$ to $n=n$ the trigger again applies the "discharged" series combination across the terminals of the winding. By proper choice of the circuit components, it is possible so to arrange that, upon occurrence of the n th event, the action of the trigger in connecting the series combination across the winding of the relay causes the state of the magnetic circuit to be modified so that the relay opens and the counting cycle will commence again, upon the occurrence of the next event.

By the term "holding current" is meant a current which, while in itself not sufficient to cause closing of the relay, will maintain the relay in closed position once it attains that state.

My invention will be described in detail in connection with the attached figure of drawings.

A relay generally represented at 1 has a winding 2 and a transfer contact generally represented at 3. The transfer contact in turn comprises a pole contact 4 and break and make contacts 5 and 6 as shown. The relay arrangement is such that, when the relay is released the pole 4 is connected to the break contact 5 whereas, when the relay is operated, the pole 4 is connected to the make contact 6. As shown in the drawing, the winding 2 of the relay is connected through resistor 10 to one terminal 11 of a direct current supply, the other end of the winding being connected to the other terminal 12 of the supply. The resistor 10 which for convenience may be variable is so selected as to ensure that there is set up in the winding 2 a "holding" current. The contacts 5 and 6 of the relay are respectively connected to the terminals 11 and 12, as shown. The circuit also includes a series resistor-condenser combination generally represented at 7 comprising a resistor 8 and a condenser 9, one terminal of which is connected to the point 12. A trigger, generally represented at 15 is for the purpose of convenience here illustrated as a single pole double throw switch having a pole contact 16 and two other contacts 17 and 18. The trigger 15 is adapted to be actuated upon the occurrence of the events to be counted. The "normal" condition of the trigger is such that the pole 16 is connected to the contact 18—i.e. the condition shown in the drawing. Upon occurrence of one of the events to be counted, the condition of the trigger is changed so that the pole 16 is connected to the contact 17. At some time during or after termination of the event the trigger returns to its "normal" condition. As will be apparent to persons skilled in the art there are many components and circuit arrangements which could be used to form a trigger having the required characteristics. As shown, the upper end of the resistor 8 is connected to the pole 16, whereas the contacts 17 and 18 are respectively connected to the junction between the winding 2 and the resistor 10 and the pole 4 of the relay 1.

Prior to the occurrence of the first event to be counted, the "condition" of the circuit is that shown in the drawing—i.e. the condenser 9 is charged through the resistor 8 as a result of being connected across the terminals 11, 12 of the source of D.C. potential. Upon the occurrence of the first event to be counted—i.e. $n=1$, the trigger 15 is actuated so as to cause the charged condenser 9 to be applied across the terminals of the winding 2 from the resistor 8. This momentarily increases the current flowing through the winding 2 so as to cause the relay to operate—i.e. causing pole 4 to be connected to make contact

6. Upon release of the trigger 15 to its normal condition, the upper end of the resistor 8 is once again connected to the pole 4 of the relay 1. Now however the circuit is such that the series combination 7 is shorted, and the condenser 9 consequently discharges through the resistor 8. Upon the occurrence of the next event $n=2$, the discharged condenser 9 is connected across the terminals of the winding 2, through the resistor 8 and this is repeated for each of the subsequent events $n=3$ to $n=n$. The successive application, across the terminals of the winding 2, of the discharged series combination (i.e. discharged condenser 9 in series with the resistor 8), has what may conveniently be called a "cumulative ferromagnetic" effect. By appropriate selection of the circuit components it is possible so to design the arrangement that, upon the occurrence of the n th event to be counted, the application of the discharged series combination 7 across the terminals of the winding 2, causes the relay to release, thus again connecting the pole 4 to the break contact 5, whereby the counting sequence can commence once more.

While I do not wish to be bound by any particular theory of operation of my invention, it would seem that the successive applications of the discharged condenser 9, in series with the resistor 8, across the winding 2 affects the "state" of the magnetic circuit of the relay in some consistently repeatable manner whereby satisfactory counting results can be obtained. The number n is apparently limited only by the number of practically distinguishable states within the ferromagnetic material. Even at relatively high values of n , the operation of my counter arrangement is, while not precisely accurate, sufficient to give useful results where only an approximate count is required.

In one specific embodiment of my invention, designed for $n=3$, the relay used was a standard Bell Telephone unit designated by the symbol "AF67." The source of D.C. potential was 48 volts. The resistor 8 and condenser 9 were respectively 1300 ohms and 3 mfd. The resistor 10 was a potentiometer adjusted to the proper holding current conditions which in this case was about 9000 ohms.

What I claim as my invention is:

1. A counting device adapted to be actuated by a trigger means comprising a relay having a winding and a transfer contact, a resistor, a resistor-condenser series combination, and a trigger adapted to be actuated upon occurrence of each of the events, said winding and said resistor being connected in series across a source of D.C. potential adapted to establish a holding current in said winding; connection means, including said trigger, for connecting said series combination across said winding upon the occurrence of each of the events to be counted, and further connection means including said trigger means and said transfer contact for charging said condenser prior to the said first event, and thereafter discharging said condenser following return of the trigger to normal position after actuation thereof by each successive event.

2. A device for counting the events $n=1$ to $n=n$ wherein n is greater than 2 comprising a relay having a winding and a transfer contact; a resistor, a resistor-condenser series combination, and a trigger means adapted to be actuated upon the occurrence of said events; said resistor and winding being connected across a source of D.C. potential adapted to establish a holding current in said winding; connection means whereby, when the relay is released, the series combination is connected across a source of D.C. potential so as to charge the condenser thereof, and when the relay is operated the series combination is shorted so as to discharge the condenser; and further con-

nection means including said trigger whereby the series combination is connected across said winding upon the occurrence of each of the said events.

3. A device for counting events $n=1$ to $n=n$ where n is greater than 2, comprising a relay having a winding and a transfer contact; a resistor, a resistor-condenser series combination, and a trigger adapted to be actuated upon the occurrence of each of the events; said resistor and winding being connected in series with a source of D.C. potential whereby a holding current is established in the winding; connection means, including said contact and said trigger, whereby (a) prior to the occurrence of the first event $n=1$ the said series combination is connected to a source of D.C. potential so as to charge the condenser (b) upon the occurrence of each of the events $n=1$ to $n=(-1)$ the said series combination is connected across the winding and is thereafter disconnected from the winding and shorted and (c) upon occurrence of the event $n=n$ the said series combination is again connected across the winding whereby the relay is released.

4. A device for counting events $n=1$ to $n=n$ wherein n is greater than 2 comprising a relay having a winding and a transfer contact; a resistor; a resistor-condenser series combination; a trigger adapted to be actuated upon occurrence of each of the events; and a source of D.C. potential; one end of the winding being connected to one terminal of the said source, the other end being connected through said resistor to the other terminal of said source whereby a holding current is established in the winding; a connection between one end of said series combination and said one terminal of said source; connection means, including said trigger means, whereby the other end of said series combination is normally connected to the transfer contact and is, upon the occurrence of each of said events connected to the other end of said winding; means connecting the transfer contact to the terminals of said source whereby, when the trigger is in normal condition, the condenser is charged by said source, when the relay is released, and the series combination is shorted when the relay is operated.

5. A device for counting n events wherein n is greater than 2, comprising; a relay having a winding and pole, break and make contacts; a resistor; a resistor-condenser series combination; a trigger adapted to be actuated upon the occurrence of each of the events, and thereafter return to a normal position; and a source of D.C. potential; means connecting one end of the winding, one end of the series combination and the make contact to one terminal of the source; means connecting the other end of the winding through said resistor to the other terminal of the source whereby a holding current is established in the winding; means connecting the break contact to the other terminal of the source; and further connection means including said trigger whereby when it is in normal condition the other end of the series combination is connected to the pole contact, and, when it is actuated by the occurrence of one of said events, the other end of the series combination is connected to the other end of the winding.
